Patented July 26, 1921.

Edward L. Megill, Inventor
By his attorney
Frank J. Kent

UNITED STATES PATENT OFFICE.

EDWARD L. MEGILL, OF NEW YORK, N. Y.

PRINTING-PRESS GAGE.

1,385,637.

Specification of Letters Patent. Patented July 26, 1921.

Application filed October 18, 1916. Serial No. 126,293.

To all whom it may concern:

Be it known that I, EDWARD L. MEGILL, a citizen of the United States, residing at New York, in the county of New York and 5 State of New York, have invented certain new and useful Improvements in Printing-Press Gages, of which the following is a specification.

This invention relates to improvements in 10 what are commonly called feed gages for use on printing presses, and which are secured to the tympan sheets on the platen of the press to serve as stops or rests, limiting the position of the sheets to be printed, 15 so that they may be properly presented to the type. I have in mind particularly the sort of gages in which there is one part that is inserted through a hole or slit in the tympan sheet, and lies below this sheet, and 20 another part connected to the first part when it overlies the tympan sheet, the sheet being gripped between these two parts. Gages of this type are usually provided with a tongue which projects through an opening in a vertical 25 head member continuous with the part that overlies the sheet, said tongue member having side walls or extensions engaging the member that overlies the sheet, and along which the tongue member is slidable. It has 30 been customary to provide stops limiting the sliding movement of the tongue in the direction away from the head member, and with such a construction it is obvious that difficulty would be experienced in case the 35 tongue were broken or in case it were desired to replace the same by another of different length. Or, if no such stop were provided the tongue member might be slid too far until it came off, in which event there 40 would be difficulty in putting it back into position, and likelihood of injuring the fingers on the exposed end of the prong.

Accordingly, one of the objects of the invention is to provide a gage of the kind referred to, including a head member having a vertical wall provided with an opening, a prong member extending from said head member and adapted to be inserted beneath the tympan sheet, an upper pressure member extending from the head member in the same direction as the prong member, and a tongue slidable to different positions along the upper pressure member and extending through the aperture in the vertical wall of 55 the head member, said upper pressure member having a stop portion for normally lim-

iting the movement of the tongue in one direction, and said pressure member being constructed to permit of the release of the tongue from the restraint of said stop when 60 it is desired to replace the tongue in case of breakage, or to substitute a tongue of different length.

Another object is to provide a construction of tongue which in itself will afford 65 elasticity and adjustability in the parts connecting it with the upper pressure member of the gage pin, so that it will hold with proper tension to the parts of the upper pressure member to which it is attached, 70 even though these parts should not be exactly true or regular, thus providing a tongue that will be interchangeable from gage pin to gage pin.

Another object is to provide a construction of upper pressure member including two parallel arms connected at one end and yieldable toward each other at the other end, with the tongue member slidably engaged 75 with both arms.

A further object is to construct the free 80 ends of the parallel arms with fingerpieces extending at right angles to the plane of the arms, whereby they may be engaged in the operation of pressing them together for 85 the release of the tongue; also to so shape the arms that their free ends may be pressed very close together, notwithstanding that their fixed ends are comparatively widely 90 separated.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claim.

In the accompanying drawings, which are to be taken as part of this specification, and in which I have shown a merely preferred form of embodiment of the invention, Figure 1 is a perspective view of a gage pin 105 embodying the invention; Fig. 2 is a perspective view of the tongue portion, detached; Fig. 3 is a top plan view of the article shown in Fig. 1; Fig. 4 is a sectional view taken on the line 4—4 of Fig. 3; Fig. 110 5 is a sectional view taken on the line 5—5 of Fig. 3; Fig. 6 is a bottom plan view of

the subject-matter of Fig. 3; Fig. 7 is an end view of the subject-matter of Fig. 3, looking toward the right; Fig. 8 is a view similar to Fig. 6 but showing the adjustable tongue in another position; Fig. 9 is a view similar to Fig. 8 showing the tongue in still another position and freed from the restraint of the stop; and Fig. 10 is a rear end view of the tongue, detached.

- 10 Referring to the numerals on the drawings, there is shown at 11 a prong part having a bent end 12 so that it may be readily inserted through the tympan sheet, making an aperture therein for itself. At its other end this prong part 11 is connected to or integral with the usual vertical head portion 14, and also connected to or integral with this head portion 14 is an upper pressure member comprising two parallel arms 15, one on each side of the prong portion 11, normally spaced apart in a predetermined relation but movable toward each other under pressure. These arms 15 are preferably integral with a bridge 16 continuous with but at right angles to the vertical head portion 14, and the arms 15 are joined to this bridge 16 by upwardly inclined portions 17. It will be understood that the prong member 11 is to be inserted into the tympan sheet, moved forwardly a desired distance, and then to have its bent end brought up through the sheet until it protrudes above the same. The arms 15 will lie entirely above the tympan sheet, and the sheet is gripped between the prong portion 11 and the upper arms 15, frictionally, to hold the gage against movement, the free end of the prong portion 11 extending upwardly toward the arms 15 at an angle, as shown in Fig. 5. When the gage is in the desired adjusted position, pressure is applied to the bridge 16, to drive down into the tympan sheet, the points 18 which are formed on the vertical head member 14.
- 15 The tongue member is shown in perspective in Fig. 2 and in end view in Fig. 10. This tongue member comprises a tongue 19, one end of which is intended to be inserted through an aperture 20 in the vertical head member 14, as indicated in Figs. 1, 3, 4, 5, 6, 7, 8 and 9. The other end is provided with a part 21, in line with the length of the tongue, and at each end of this part 21 there is a hook part 22, the junction of which with the part 21 is defined by a sharp bend, for the sake of increased resiliency. When the tongue is in position, with one end projecting through the aperture 20, the hooks 22 are supposed to be engaged over the edges of the flat arms 15. It is evident that the tongue may now be adjusted so as to project a greater or less extent through the opening 20, (compare Figs. 6, 8 and 9). In order to facilitate this sliding adjustment 60 of the tongue, the end thereof, that is the end

of the part 21 between the hooks 22, is bent up sharply at right angles as indicated at 24 to provide a fingerpiece. When the tongue member is pushed toward the left (referring to Fig. 1) it is evident that its limit of movement in that direction is fixed by the inclined parts 17, which act as stops; and in order to limit the movement of the tongue in the other direction, that is to the right in Fig. 1, the arms 15 are provided with down-turned side flanges 25, past which the hooks could not move except for the fact that on account of the resiliency of the material of which the device is made, particularly the arms 15 and their connection to the bridge 16, the free ends of the arms may be moved toward each other, through their normal tendency is to spring apart to the position shown in Fig. 8. It is evident that as the tongue member is slid from the Fig. 8 position to the Fig. 9 position, these hooks will exercise a frictional hold upon the arms, thus assuring the retention of the tongue in any position to which it may be brought, and compensating for slight irregularities in size of parts, etc. To remove the tongue part entirely it is necessary merely to grasp the ends of the arms 15 and exert pressure against the flanges 25 sufficient to force the free ends of the arms more closely together to such an extent that one or both of the hooks 22 may be disengaged from about the edge portion or portions of the arm or arms 15 (see Fig. 9), whereupon the hook end of the tongue may be lifted up and the other end entirely withdrawn from the opening 20 for purposes of repair or replacement or substitution. In replacing, the tongue end is first pushed through the opening 20, beneath the bridge 16, and then the free ends of the arms 15 are pressed together sufficiently to allow of the engagement of the hooks 22 with the edges of and underneath the arms, whereupon the pressure upon the arms 15 is released and the edges of the arms snap into the hooks and hold themselves by friction, as already described. The hooks 22 are so shaped and so joined to the part 21 of the tongue that they are given a certain resiliency so that the hooks will accommodate themselves to slight irregularities, for instance, in thickness of arms, or in extent of openings in the hooks, or in regard to the parallelism of the arms; furthermore, the hooks are made resilient (see full and dotted line positions of Fig. 10) to compensate for differences in the spread of the arms 15, that is, the hooks have an elastic grip on the arms, due to their own inherent resiliency or to the resiliency of the arms, or to both factors. And in order that the free ends of the arms 15 may be brought as close together as possible, I prefer to bevel the inner edges of the arms, as indicated at 26.

It will be understood of course that the

spaces between the arms 15 and the tongue are wider than the length of the turned-under hooks 22, so that the arms may be pressed together sufficiently to allow of the

5 release of the hooks.

The downturned flanges 25 on the outer edges and at the ends of arms 15 have the effect of keeping the ends of the arms above and spaced away from the tympan when the 10 device is in use. With prior devices of this kind, in which the ends of the arms rest on the tympan sheet, the effect was to produce something very like a shearing action on the tympan sheet, especially if the latter were 15 thin, between the edges of the arms on the one hand and the edges of the prong on the other hand. Incidentally, these vertical flanges 25 serve as finger-pieces for compressing the arms toward each other. If the 20 arms were not provided with a flange the arms, especially if bent downward at the ends, would be likely to twist in the fingers under pressure, besides giving pain and discomfort.

25 Furthermore, these flanges 25, because of their location, permit of a considerable extent of movement of the arms toward each other without striking the prong. And they serve as stops, to prevent the hooks from 30 sliding off the ends of the arms.

It will be evident that I have provided a construction in which the adjustable tongue will be held in any adjusted position; from which there is no danger of the tongue accidentally slipping off and getting lost; and from which the tongue may be removed for purposes of repair or replacement, when desired, without inconvenience and danger of injury to the fingers.

40 Inasmuch as many changes could be made in the above construction, and many apparently widely different embodiments of my invention could be made without departing from the scope thereof, it is intended that all

matter contained in the above description or 45 shown in the accompanying drawings shall be interpreted as illustrative and not in a limiting sense.

It is also to be understood that the language used in the following claim is intended to cover all the generic and specific features of the invention herein described and all statements of the scope of the invention which, as a matter of language, might be said to fall therebetween. 55

I claim:

In a device of the kind described, a head member having a vertical wall provided with an opening, a prong member extending from said head member and adapted to 60 be inserted beneath a tympan sheet, parallel flat arms extending from the head member in the same direction as the prong member and normally spaced apart in a predetermined relation but movable toward each 65 other under pressure, and a tongue member 70 slideable above and to different positions along said arms and having turned-under hook portions engaging the edges of and beneath the arms when the arms are in their normally spaced relation, said arms being 75 movable toward each other under pressure a sufficient distance to permit of the engagement of the turned-under hooks with the edges and under sides of the arms, or the release of the hooks from such engagement, 80 said tongue member being located intermediate the arms and the spaces between the arms and the tongue being wider than the length of the hooks, said arms at their free 85 ends having downwardly turned side flanges on their outer edges serving as finger pieces to move the arms toward each other and also acting as stops to prevent the hooks from sliding off the ends of the arms. 85

In testimony whereof I affix my signature.

EDWARD L. MEGILL.
